UNITED STATES PATENT OFFICE.

CELIA KOHLMAN, OF NEW YORK, N. Y.

DESIGN FOR A WAIST-BELT.

SPECIFICATION forming part of Design No. 28,450, dated April 5, 1898.

Application filed December 9, 1897. Serial No. 661,323. Term of patent 14 years.

To all whom it may concern:

Be it known that I, CELIA KOHLMAN, a citizen of the United States, residing in New York city, county and State of New York, have invented and produced a new and original Design for a Waist-Belt, of which the following is a specification.

My invention relates to a new and original design for waist-belts; and it consists in the disposition and configuration of the parts hereinafter described and shown.

Reference is to be had to the accompanying drawing, which is a perspective view of a waist-belt embodying my invention.

The leading feature of my design consists in a waist-belt having a series of puff-like protuberances upon its external surface, located at distances apart, and a fastening at the separated portions of the belt, the main body portion of the belt being rectangular, provided with a flat face, and having a series of slots or apertures forming cross-bars that lie between the upper and lower straight edges of the belt, between which bars the material forming the puffs is located.

In the accompanying drawing the letter A

indicates the main body of a belt, which is rectangular, having a flat face and straight upper and lower edges and provided with a series of slots or apertures B, arranged in pairs, and between these pairs of slots are cross-bars C.

D is a strip of material that is threaded through the slots or apertures B, showing partly on the outer and partly on the inner 35 surface of the belt A, the portion D' of which strip, that lies on the exterior of the belt between cross-bars C, being arranged in the form of puffs, that project outwardly beyond the flat face of the belt. Thus the exterior 40 of the belt has the appearance of a plurality of puffs in the form of protuberances on the surface thereof. The belt is separate at one part and is there provided with a fastening E.

I claim—

The design for a waist-belt, substantially as shown and described.

CELIA KOHLMAN.
